Des. 207,178
Patented Mar. 14, 1967

207,178

COMBINED LUMINAIRE AND GUARD THEREFOR

Leonard Atkin, Springfield, and Richard Sangiamo, Roselle Park, N.J., assignors to Stonco Electric Products Company, a corporation of New Jersey

Filed July 19, 1966, Ser. No. 3,132

Term of patent 14 years

(Cl. D48—4)

FIG. 1

FIG. 2

FIG. 3

FIG. 4

FIG. 5

FIG. 6

FIG. 7

FIG. 8

FIGURE 1 is a front elevational view of a combined luminaire and guard therefor showing our new design;

FIGURE 2 is a side elevational view thereof;

FIGURE 3 is a top view thereof;

FIGURE 4 is a bottom view thereof;

FIGURE 5 is a rear elevational view thereof;

FIGURE 6 is a side elevational view of the lamp guard element of the design as shown in FIGURE 1;

FIGURE 7 is a top view thereof; and

FIGURE 8 is a bottom view thereof.

We claim:

The ornamental design for a combined luminaire and guard therefor, substantially as shown.
